UNITED STATES PATENT OFFICE

163,410

MICROSCOPE

Leslie J. Peters, Lancaster, and John T. Armbruster, Niagara Falls, N. Y., assignors to American Optical Company, Southbridge, Mass., a voluntary association of Massachusetts

Application February 1, 1951, Serial No. 14,072

Term of patent 14 years

(Cl. D57—1)

To all whom it may concern:

Be it known that we, Leslie J. Peters and John T. Armbruster, citizens of the United States of America, residing at Lancaster and Niagara Falls, in the counties of Erie and Niagara, respectively, and State of New York, have invented a new, original, and ornamental Design for Microscope, of which the following is a specification, reference being made to the accompanying drawings, forming a part thereof.

In the drawing:

Fig. 1 is a perspective view of a microscope, showing our new design; and

Fig. 2 is a plan view thereof.

The characteristic features of our new design reside in the portions shown in full lines in the drawing.

We claim:

The ornamental design for a microscope, substantially as shown and described.

LESLIE J. PETERS.

JOHN T. ARMBRUSTER.
